WATER-DISTRIBUTING SYSTEM FOR CONCRETE MIXERS

Clarence I. Bohmer and Robert F. Gatch, Columbus, Ohio, assignors to The Jaeger Machine Company, Columbus, Ohio, a corporation of Ohio

Application March 30, 1938, Serial No. 198,968

2 Claims. (Cl. 259—168)

Our invention relates to a water-distributing system for concrete mixers. It has to do, more particularly, with a water-distributing system adapted to be applied to the rotating drum of a concrete mixer such as a truck mixer. However, it is to be understood that our invention is not necessarily limited to mixers for concrete but is applicable to mixers for other material and it is also not limited to the distribution of water in the mixer since it can be used for distributing other liquids.

One of the objects of our invention is to provide a device adapted to be applied to the drum of a concrete mixer for distributing water within the interior thereof, said device including a mechanically operated valve which can be readily opened and closed at all times and with which the concrete in the mixing drum will not interfere.

Another object of our invention is to provide a device of the type indicated embodying a valve which is so constructed and arranged that the parts thereof will not be subject to any appreciable wear.

In its preferred form, our invention contemplates the provision of a water-distributing system which is associated with a rotating mixing drum such as the rotating drum of a truck mixer. A water pipe is axially disposed within the mixing drum and is mounted in such a manner that it will rotate with the drum. On this axially disposed water pipe at a suitable point we dispose a water-distributing bell. Within this bell, we provide a valve which controls the flow of water from the bell. This valve is positively and mechanically opened by means outside of the drum and automatically closed by means inside the drum. Such means is so constructed that it will not interfere with rotation of the drum. The operating means for the valve can be actuated to positively seat or unseat the valve without interference by the material within the drum. The valve is so disposed within the bell that it is protected from the material within the drum. Furthermore, it is so constructed that the parts thereof will not wear to any appreciable extent.

The preferred embodiment of our invention is illustrated in the accompanying drawing wherein similar characters of reference designate corresponding parts and wherein:

Figure 1 is a side elevation, partly broken away, illustrating a truck mixer having a water-distributing system according to our invention associated therewith.

Figure 2 is a detail mainly in longitudinal section but partly in side elevation showing the valve and the operating means therefor.

Figure 3 is a detail in perspective showing several parts of the valve and water bell in disassembled relationship.

With reference to the drawing, in Figure 1 we have shown our water-distributing system applied to a mixer for concrete of the truck mixer type. However, it is to be understood that our invention is not limited to this particular type of mixer.

The truck mixer is shown as comprising a mixing drum 1 which is mainly of cylindrical form but which has frusto-conical ends 2. This mixing drum is rotatably mounted on the truck chassis in the usual way. It is driven by a power unit 3 to which it is connected in the usual manner. A water tank 4 is supported at a comparatively high point on the truck mixer and is adapted to supply water for distribution in the mixing drum under a gravity pressure. However, in some instances it may be desirable to provide a pump for this purpose. A valve 5 may be provided for controlling the flow of water from the tank.

Within the mixing drum a water pipe 6 is axially disposed. This water pipe has both its forward and rear ends carried by the mixing drum in such a manner that the pipe will rotate with the mixing drum. The pipe 6 is divided into two sections, viz., a rear section 7 and a forward section 8. The rear section 7 is a dummy section and does not carry water. The rear end of the section 7 may carry, as indicated at 9, means for controlling the opening and closing of the discharge door provided at the rear end of the mixing drum.

Between the adjacent ends of the pipe sections 7 and 8 we provide a water-distributing bell 10. This bell 10 is of frusto-conical form, as shown, and is provided with a threaded boss 11 on its smaller end for receiving the threaded end of the pipe section 8. A spider 12 is bolted to the larger end of member 10 by means of bolts 13. This spider has a threaded boss 14 formed centrally thereon adapted to receive the threaded end of the pipe section 7. Within the bell adjacent the inner end thereof a substantially cylindrical chamber 15 is formed. At the outer end of this chamber an annular seat 16 is provided for receiving a strainer member 17 which takes the form of a perforated disk. This disk has a centrally disposed boss having an opening 18 extending therethrough. A rod 19

extends through this opening and is free to slide therein. The rear end of this rod carries a member 20 which is of substantially disk-like form but which is slightly concavo-convex. This member 20 is preferably made of non-corrosive metal. It is also preferably resilient. When in the position indicated in Figure 2, its outer edge is adapted to seat on an annular seat 21 surrounding the strainer member 17. The member 20 is prevented from moving longitudinally on the rod 19 by means of the nuts 22 threaded on the outer end thereof. A spring 23 is provided for normally holding the valve disk 20 seated on the annular seat 21. This spring 23 is a compression spring which surrounds the rod 19. Its rear end bears against the boss 18 of the member 17 while its forward end bears against a collar 24 keyed to the rod 19.

The forward end of the pipe section 8 is threaded into the rear end of a sleeve 25 carried by a disk 26 which is secured to the forward end of the mixing drum 1 in such a manner that it will rotate therewith. The forward portion of this sleeve is disposed within a roller bearing 27. A pipe section 8a extends into the forward portion of the sleeve 25 and a packing gland arrangement 28 is provided for preventing leakage of water around the pipe section 8a. It will be apparent that the pipe section 8 is free to rotate relative to the pipe section 8a. The pipe section 8a is connected by a flexible hose 8b to another pipe section 8c. This pipe section 8c extends into a fitting 29 which is connected to the discharge pipe leading from the water tank 4. Plastic packing material is provided in an annular groove 30 formed within the fitting 29 around the pipe section 8c. This plastic packing material is compressed by means of an adjustable bolt 31. It will be noted that the rod 19 extends forwardly through the pipe sections 8, 8a, 8b, 8c and through the fitting 29. A chamber 32 is formed within the fitting 29 around the rod 19 for receiving plastic packing material which may be compressed by an adjustable bolt 33. The rod 19 is adapted to be moved rearwardly by means of a hand lever 34 pivoted to lugs 35 carried by the fitting 29. It will be apparent that if the lever 34 is forced rearwardly, the rod 19 will be forced rearwardly unseating the disk 20 from the seat 21. As soon as the lever 34 is released, the springs 23 will automatically seat the disk 20 and close the valve. If desired, suitable means may be provided for releasably holding the lever 34 in its rearwardmost position. With this device, whenever it is desired to supply water to the mixing drum, the lever 34 is actuated to move the rod 19 rearwardly and unseat the valve disk 20. The water will then flow from the tank 4 through fitting 29, pipe sections 8c, 8b, 8a and 8 into the bell 10. The water will flow through the bell past the outer periphery of the disk 20 and will be discharged into the mixer. Because the disk 20 is disposed within the bell, it will be protected from the concrete. If any concrete enters the bell, it will tend to be deflected away from the valve seat due to the fact

that the member 20 has a rear surface of convex form. As soon as sufficient water is supplied to the mixed, the lever 34 may be released and the spring 23 will force the rod 19 forwardly seating the disk 20 on the annular seat 21. Because the disk 20 is resilient, this will insure that it will be positively seated. It will be apparent that when the bell 10 and the pipe section 8 rotate, the rod 19 and the disk 20 will rotate therewith. The pipe section 8a and the fitting 29 will remain stationary, the rod 19 rotating therein without interference therewith. The forward end of the rod is free from the lever 34, the lever merely bearing thereagainst, in order to permit this rotation.

It will be apparent from the above description that we have provided a water-distributing device having many advantages. The valve is mechanically operated and can be readily opened and closed at all times. The concrete in the mixing drum will not interfere with the opening and closing of this valve. The valve is so constructed and arranged that the parts thereof will not be subject to any appreciable wear.

Various other objects and advantages will be apparent from the preceding description, the drawing and the following claims.

Having thus described our invention, what we claim is:

1. In combination, a mixer, a water-distributing system, said water-distributing system including a pipe supported axially within the mixing drum, said pipe being composed of front and rear sections, a water-distributing device between the ends of the adjacent sections, said water-distributing device comprising a housing mounted on the forward section of the pipe, said housing being of substantially frusto-conical form and being directed rearwardly, a spider secured to the rear end of said housing and connected to the rear section of the pipe, a valve disk disposed within said housing, a seat for said disk, said disk having a convex surface on the side opposite the valve seat, and a rod connected to said disk and extending through the front section of said pipe to a point outside of said mixing drum for actuating said valve disk.

2. In combination, a mixer, a water-distributing system, said water-distributing system including a pipe supported axially within the mixing drum, said pipe being composed of front and rear sections, a water-distributing device between the ends of the adjacent sections, said water-distributing device comprising a housing mounted on the forward section of the pipe, said housing being of substantially frusto-conical form and being directed rearwardly, a spider secured to the rear end of said housing and connected to the rear section of the pipe, a valve disk disposed within said housing, a seat for said disk, and a rod connected to said disk and extending through the front section of said pipe to a point outside of said mixing drum for actuating said valve disk.
